HANGER FOR A PLANT CONTAINER

Leonard Entin and Leon A. Gainsboro, Wayland, Mass.,
assignors to Opus, Incorporated, Boston, Mass.

Filed Oct. 9, 1974, Ser. No. 513,457

Term of patent 14 years

Int. Cl. D6—04

U.S. Cl. D6—137

FIG. 1

FIG. 2

FIG. 3

FIG. 4

FIG. 1 is a side elevation view of a hanger for a plant container, showing our new design, a portion of a wall and the head of screw shown in broken lines for illustrative purposes only;

FIG. 2 is top plan view thereof;

FIG. 3 is an enlarged fragmentary end view thereof; and

FIG. 4 is an enlarged cross-sectional view thereof taken on line 4—4 of FIG. 1.

We claim:

The ornamental design for a hanger for a plant container, as shown and described.
